UNITED STATES PATENT OFFICE.

WILLIAM A. WILSON, OF MURPHYSBORO, ILLINOIS.

AUTOMATIC CAR-HOLDING DEVICE.

SPECIFICATION forming part of Letters Patent No. 678,209, dated July 9, 1901.

Application filed December 22, 1900. Serial No. 40,819. (No model.)

To all whom it may concern:

Be it known that I, WILLIAM A. WILSON, a citizen of the United States, residing at Murphysboro, in the county of Jackson, State of Illinois, have invented certain new and useful Improvements in Automatic Car-Holding Devices, of which the following is a specification, reference being had therein to the accompanying drawings.

10 This invention relates to automatic car-holding devices, and particularly to such a device adapted to automatically engage and release a mining-car when upon a hoisting-platform or other movable support.

15 The invention has for an object to provide means for automatically engaging the wheels of a car after the same has reached its proper position upon the platform and for releasing such means when the car is to be removed 20 from said platform.

A further object of the invention is to provide an automatic device for stopping and holding the car in position for engagement by the retaining devices.

25 A further object of the invention is to provide means to be operated by the car for returning the stopping device to its initial position for engagement with the wheels of a subsequent car.

30 Other and further objects of the invention will hereinafter appear in the following specification, and the novel features thereof will be pointed out in the appended claims.

In the drawings, Figure 1 is a plan showing 35 my invention applied to a platform. Fig. 2 is a side elevation of the platform with a car thereon and the restoring device in operative position, and Fig. 3 is an end elevation showing in full lines the position of the holding-dogs when shifted to release a car.

40 Like letters of reference refer to like parts in the several figures of the drawings.

The invention may be applied to any desired support and in the present case is illustrated in connection with a platform or cage Q, such as is ordinarily used in mine-elevators, upon which the car containing material is placed. At one side of the center of this 45 platform a pivoted chock or tumbler A is mounted, preferably by means of a depending bracket A' from the under side of the

platform. This chock is formed at its upper end with a contact-face A² and at its lower portion with a weight A³, by means of which it is normally held in the position shown by 55 full lines in Fig. 2, but may be depressed below the track Q' by the wheel of the car, as shown by dotted lines in said figure, and afterward rises behind the wheel to hold the same. The chock is prevented from moving 60 downward below the track in a direction opposite to that shown by dotted lines in Fig. 2 by the wall of the recess within which it moves, which acts as a stop to limit the movement in that direction. Operating in connection with these chocks are keepers C, pivoted at C' to the platform and provided at one 65 end with a contact-shoe C² for the wheel. The opposite end of each keeper forms a lever C³, by means of which the keeper may be operated. My invention contemplates the use of one or more of these keepers, and when two of the same are used they are preferably connected together by means of the crank-arms G, extending from the shaft F and connected 70 with the levers C³ by means of the pivoted links E. The lower end of the shaft F is provided with a crank-arm H, from which an operating-rod I extends to the edge of the platform and is suitably supported and guided 75 by means of a keeper I'. This rod may be operated by any desired means, one form of which will be hereinafter described, and an inward movement of the rod by means of the connections just described throws the shoes 80 C² into position over the track upon the platform.

For the purpose of securely retaining the car in proper position upon the platform a holding-dog D has been provided and one or 90 more of the same may be used, as found desirable. This dog is pivotally mounted at D' in brackets D² and provided at its lower portion with a weight W, carried by a curved arm D³, so disposed as to normally throw the 95 holding-dog into position over the track, as shown by dotted lines in Fig. 3. The dog D may be of any suitable configuration, preferably looped, as shown, and offset, as at D⁴, to permit the loop to accurately and closely engage the tread of the wheel. When the loop assumes the position shown by dotted lines in 100

- Figs. 1 and 3, the edge thereof engages the lever C^2 of the keeper, as shown at r , thereby throwing the shoe of the keeper outward from the track, as shown by dotted lines in Fig. 1.
- 5 This permits the car to be rolled from the platform as soon as the holding-dogs are released. If the car is to be removed from the platform or cage at the top of a mining-shaft, the cage will be permitted to rest upon some fixed sup-
- 10 port—such, for instance, as shown at O in Fig. 3, by means of which the weights upon the dogs are supported and the dogs shifted to the position shown by full lines in Fig. 3. A similar action occurs when the cage reaches
- 15 the bottom of a shaft and contacts with a fixed stop O . The weights used upon the dogs and also upon the chocks may be replaced by springs, which are well-known mechanical equivalents.
- 20 When the car has been released and is rolled from the cage, its wheel engages a track-cam B , which constitutes a restoring device for the keepers. The cam is provided with a bell-crank arm B' , having its free end located
- 25 in a notch formed in a bolt or push-pin L . This pin is normally retracted and the cam B elevated by means of a coiled spring M , bearing against the head L' of the pin and a fixed support. In Fig. 2 the cam is shown as
- 30 depressed and the pin projected, as when a wheel is resting thereon, and the elevated position of the cam is indicated by dotted lines. The contact end of the pin L bears against a head I^2 , formed upon the end of the rod I , and
- 35 when projected restores the keepers to their position for engaging the next car rolled upon the platform or cage.
- In the operation of the invention if the platform be at the bottom of a shaft the car rolled
- 40 thereon will engage the shoe C^2 of the keepers, the parts being in the position shown in Fig. The chocks A are also depressed as the wheel passes over the same and rise behind the wheel, (see Fig. 2,) so that the car is centered upon the platform. As soon as the platform rises to release the weights of the holding-dogs from their supports said weights throw the dogs inward into contact with the car-wheel, (see dotted line, Fig. 3,) and at the same
- 45 time the keepers are thrown outward away from the wheels which they first engaged. When the car is to be removed from the platform, the dogs are released in any desired manner—for instance, by the support O —and the
- 50 car rolled from the platform onto the track-cam B , which automatically shifts the keepers into position for receiving and centering the next car placed upon the platform. It will thus be seen that the operation of the device
- 55 is entirely automatic and a correct centering of the car upon the platform secured, so that the holding devices may grasp the wheels. Furthermore, when the car is removed from the platform the parts are restored to their
- 60 initial position and ready for further operation. While the present invention is capable of use in any desired relation, it has been

found particularly advantageous for operation in connection with the holding-dog disclosed in my Patent No. 656,279, dated August 21, 1900.

It is obvious that changes may be made in the details of construction and configuration of the several parts without departing from the spirit of the invention as defined in the appended claims.

Having described my invention and set forth its merits, what I desire to claim and secure by Letters Patent is—

1. A car-holding device comprising a platform, a pivoted keeper thereon having a shoe adapted to engage a car-wheel, means for holding a wheel of said car and shifting said keeper from the wheel held thereby, and means operated by a wheel-contact beyond the keeper for restoring said keeper to its initial position; substantially as specified.

2. A car-holding device comprising a platform, a pivoted keeper thereon having a shoe adapted to engage a car-wheel, means for holding a wheel of said car and shifting said keeper, means for restoring said keeper to its initial position, and means for normally moving said holding means toward said wheel; substantially as specified.

3. A car-holding device comprising a platform, a pivoted keeper thereon having a shoe adapted to engage a car-wheel, means for holding a wheel of said car and shifting said keeper, means for restoring said keeper to its initial position, and a pivoted chock adapted to engage a car-wheel in connection with said keeper; substantially as specified.

4. A car-holding device comprising a platform provided with a track thereon, a holding-dog pivotally mounted on said platform below said track and adapted to swing inward to embrace a wheel of a car, and means to automatically throw said dog in contact with said car-wheel in the movement of the platform, and a keeper having a portion in the path of said dog to shift said keeper from engagement with a wheel in the movement of the dog toward another wheel; substantially as specified.

5. A car-holding device comprising a platform provided with a track thereon, a holding-dog pivotally mounted on said platform and adapted to engage a wheel of a car, means to normally hold said dog in contact with said car-wheel, and a pivoted keeper adapted to engage a car-wheel and provided with a lever adapted to be engaged by said dog to shift the keeper from said wheel; substantially as specified.

6. A car-holding device comprising a platform provided with a track thereon, a holding-dog pivotally mounted on said platform and adapted to engage a wheel of a car, means to normally hold said dog in contact with said car-wheel, a pivoted keeper adapted to engage a car-wheel and provided with a lever adapted to be engaged by said dog to shift the keeper from said wheel, and means inde-

pendent from said platform for restoring said keeper to its initial position; substantially as specified.

7. In a car-holding device the combination with a platform provided with a track, of a pivotally-mounted chock adapted to engage a car-wheel, means for restoring said chock to its initial position when depressed, and a keeper adapted to engage the wheel engaged by said chock at the opposite side thereof; substantially as specified.

8. In a car-holding device the combination with a platform provided with tracks, of oppositely-located keepers adapted to travel in a horizontal plane toward and from each other and having upwardly-extending shoes disposed in the path of said tracks, levers at the opposite ends of said keepers, a pivoted shaft provided with crank-arms, links extended from said arms to said levers, a crank upon the lower portion of said shaft, and an operating-rod extending from said crank toward the edge of said platform; substantially as specified.

25 9. In a car-holding device the combination with a platform provided with tracks, of oppositely-disposed keepers having shoes disposed in the path of said tracks, levers at the opposite ends of said keepers, a pivoted shaft provided with crank-arms, links extended from said arms to said levers, a crank upon the lower portion of said shaft, an operating-rod extending from said crank toward the

edge of said platform, means for engaging said levers to shift said shoes from the tracks, and means for engaging said rod to restore said shoes to their initial position; substantially as specified.

10. In a car-holding device, the combination with a platform provided with wheel-holding devices, of a track-cam located upon a fixed support and provided with a crank-arm, a push-pin normally retracted under tension, and means carried by said platform whereby said pin is adapted to shift said holding devices; substantially as specified.

11. In a car-holding device, the combination with a platform having tracks thereon, of a pivoted holding-dog adapted to embrace a car-wheel, a curved arm at a lower portion of said dog provided with a restoring-weight, a pivoted keeper provided at one end with a shoe and at its opposite end with a lever adapted to be engaged by said dog in its movement, a pivoted chock located adjacent to said keeper and provided with a restoring-weight, and means for restoring the said keeper when shifted by said dog; substantially as specified.

In testimony whereof I affix my signature in presence of two witnesses.

WILLIAM A. WILSON.
